Attorney

UNITED STATES PATENT OFFICE

SAMUEL R. PRUGH, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed June 30, 1927. Serial No. 202,619.

The present invention relates to refrigerators, and particularly to refrigerators in which the mechanical apparatus and the compartment cooled thereby are contained within one cabinet.

In refrigerators of the above type it is desirable to cool the condenser of the refrigerating apparatus by air, and since refrigerators are often placed against the walls of a room, it is desirable to expel the air from the same side of the cabinet in which the door opening for the storage compartment is disposed. One of the objects of the present invention is to prevent the relatively warm air which is expelled from the machine compartment from entering the storage compartment when the door of said latter compartment is open.

It is another object of the invention to direct the air leaving the condenser or machine compartment away from the air entering the machine compartment so that the relatively warm air will not be recirculated about the condenser.

Further objects and advantages of the present invention will be apparent from the following description, reference being had to the accompanying drawing, wherein a preferred form of the present invention is clearly shown.

In the drawing

Fig. 1 is a front view of my improved refrigerator showing the door of the storage compartment open, and

Fig. 2 is a top plan view of the refrigerator showing the machine compartment thereof in section, the section being taken on line 2-2 of Fig. 1.

Referring to the drawing, 20 indicates a refrigerator which is substantially the same as that shown in the copending application of Harry B. Hull, Serial No. 147,862, filed Nov. 12, 1926. Cabinet 21 includes a storage compartment 22 and a machine compartment 23 which are separated by a horizontal wall 24. The cabinet may be rectangular in horizontal cross section, thus having four vertical outer walls, the front wall 26 of which is provided with a door opening 27 and is closed by a door 28. This

front wall is also provided with two sets of openings or passages 29 and 30 which are formed by slitting vertically the sheet metal front wall and forming louvers 31 and 32.

The condenser 33 is disposed within the machine compartment 23 and comprises a plurality of turns of copper tubing vertically spaced from one another and for the purpose of illustrating the present invention, the condenser is herein shown as forming a part of a refrigerating apparatus of the compressor-condenser-expander type in which a compressor 35 draws refrigerant from an evaporator 34, contained within the storage compartment 22, and forces the compressed refrigerant into the condenser 33. The compressor 35 is driven by an electrical motor 36 through a belt 37 connected with the motor pulley 38 and flywheel 39 of the compressor. A fan 40 is carried on the armature shaft of the motor and is disposed within the turns of the condenser 33. Rotation of this fan causes air to be drawn inwardly through the passages 29 and about the condenser 33 and expelled through the passages 30. A portion of the air entering the machine compartment will flow transversely across the coil and about the compressor and motor and transversely across the opposite end of the condenser and in the opposite direction while another portion of this air will flow longitudinally over the turns of the condenser.

The passages 29 preferably extend in a vertical direction and the louvers 32 are arranged to direct the air sideways away from the air inlet passages 29 and away from the door opening 27. In this manner relatively warm air leaving the machine compartment will not enter the storage compartment 22 when the door 28 is open while the refrigerating apparatus is operating. Likewise, the louvers 32 direct the air away from the passages 29 so that the relatively warm air will not recirculate within the machine compartment and the louvers 31 are arranged so that relatively cool air will be taken into the passages 29 from a direction opposite the direction of the flow of expelled air.

While the form of embodiment of the in-

vention as herein disclosed, constitutes a preferred form, it is to be understood that other forms might be adopted, all coming within the scope of the claims which follow.

5. What is claimed is as follows:

1. A refrigerator comprising a cabinet rectangular in cross section having a storage compartment, a machine compartment and four vertical outer walls, one of said walls of 10 said cabinet having a door opening for the storage compartment and an opening in the machine compartment, an air cooled condenser within the machine compartment, means for circulating air outwardly from the machine compartment through said latter opening, and means for directing said air sideways away from the door opening.

2. A refrigerator comprising a cabinet rectangular in cross section having a storage 20 compartment, a machine compartment and four vertical outer walls, one of said walls of said cabinet having a door opening for the storage compartment and a plurality of louvered openings for conducting air outwardly 25 from the machine compartment, an air cooled condenser within the machine compartment, means for circulating air outwardly from the machine compartment through said louvered openings, the louvers being arranged for directing air sideways away from the door 30 opening.

3. A refrigerator comprising a cabinet rectangular in cross section having a storage compartment, a machine compartment and 35 four vertical outer walls, one of said walls of said cabinet having a door opening for the storage compartment and a plurality of louvered openings for conducting air outwardly from and inwardly into the machine compartment, an air cooled condenser within the machine compartment, means for circulating air outwardly from and inwardly into the machine compartment through said louvered 40 openings, the louvers being arranged for directing air sideways away from the door opening, the louvered openings conducting the air outwardly being directed in a direction opposite from that of the louvered openings 45 conducting the air inwardly.

50. In testimony whereof I hereto affix my signature.

SAMUEL R. PRUGH.
